23 Claims

ABSTRACT OF THE DISCLOSURE

An automated stripping assembly for cathode plates in an electrolytic metal recovery operation. Stripping is accomplished by hydraulic nozzles within a protective enclosure. The cathodes are carried individually in-line through the enclosure by a cathode conveyor that operates continuously. Cathodes are supplied in groups from carriers on a supply conveyor, each group of cathodes being fed to a delivery unit that transfers them individually to a loader that places the cathode units on the cathode conveyor. After stripping and removal of the metal, the cathodes are brought to an unloader that transfers each cathode to a receiving unit that grips the cathodes for return to the supply conveyor apparatus. The entire apparatus is functionally related to serve automatically in the stripping operation, which previously has been a manual operation.

SUMMARY OF THE INVENTION

The apparatus described herein relates to an automated stripping assembly for removal of metal from cathode plates, such as those used in the recovery of zinc by electrolytic processes. It includes several components described individually herein, each component being functionally interrelated to the stripping mechanism and to the supply conveyor for the metal-laden and stripped cathode assemblies. The stripping mechanism involves the combination of a continuously moving conveyor for the individual cathode assemblies, whereby the assemblies are moved longitudinally parallel to the cathode plate side faces. The cathode assemblies are moved across a manifold at which hydraulic and pneumatic jets are directed at the upper end of the deposited metal covering. The metal is thereby stripped from the cathode plate and received on a conveyor belt for further processing. The cathodes are individually loaded onto supporting hangers of the cathode conveyor by a loading mechanism that receives cathodes individually from a delivery unit in the form of a walking beam structure that steps cathodes to the loader. A movable track assembly is utilized to transfer carriers containing groups of cathode assemblies from a supply conveyor to the delivery unit. After stripping, each cathode assembly is individually removed from the cathode conveyor hangers and placed upon a receiving unit that collects a group of cathode assemblies, again utilizing a walking beam apparatus. A second transfer unit involving a section of movable track moves a supporting carrier beneath the grouped cathodes and returns the stripped cathode as a group to the return flight of the supply conveyor.

It is a first object of this invention to provide a completely automated and mechanized apparatus for stripping cathodes in an electrolytic operation.

Another object of the invention is to provide an apparatus for hydraulically removing deposited metal from cathode plate surfaces in which the cathodes move continuously along a conveyor during the stripping operation. One object is to eliminate the necessity of stopping the cathode movement during the stripping function.

Another object of the invention is to provide an im-

2

proved manifold and nozzle arrangement for hydraulic stripping of deposited metal on cathode plate surfaces.

Another object of the invention is to provide an apparatus for receiving the stripped metal to eliminate handling of the metal at the stripping area.

Another object of the invention is to provide a novel transfer apparatus for transferring groups of cathodes to and from a supply conveyor utilizing a continuously moving chain. The individual carriers are automatically located on moving track sections which are swung downward and outward with relation to support members of delivery and receiving units that serve as intermediate stationary supports for the cathode.

Another object of the invention is to provide a unique loading apparatus for individually placing the cathodes on a continuously moving conveyor feeding into the stripper mechanism. Another object of the invention is to provide a unique unloading apparatus for removing the individual cathode assemblies from the cathode conveyor without interrupting movement of the conveyor, including safety controls to automatically detect malfunctions of the apparatus.

These and further objects will be obvious from the following description and the discussion of the operation of the various components. It is to be understood that the details disclosed herein are not intended to limit the scope of the disclosure or the invention as set out in the appended claims.

DESCRIPTION OF THE DRAWINGS

FIG. 1 is a schematic plan view of the apparatus, showing the various components in simplified form;

FIG. 2 is a side elevation of the apparatus as seen along line 2—2 in FIG. 1;

FIG. 3 is a side elevation of the stripper enclosure as seen generally along line 3—3 in FIG. 1;

FIG. 4 is an end elevation view of the stripper enclosure as seen along line 4—4 in FIG. 3;

FIG. 5 is a vertical sectional view through the enclosure as seen along line 5—5 in FIG. 3;

FIG. 6 is an enlarged plan view within the enclosure looking downward at the hydraulic stripping mechanism;

FIG. 7 is a longitudinal sectional view taken along line 7—7 in FIG. 6;

FIG. 8 is a transverse sectional view taken along line 8—8 in FIG. 6, including the associated cathode conveyor and cathode assembly devices;

FIG. 9 is a side elevation view taken along the portion of the supply conveyor generally as designated by line 9—9 in FIG. 1;

FIG. 10 is an enlarged fragmentary view of an accumulator as seen along line 10—10 in FIG. 9;

FIG. 11 is an enlarged vertical sectional view immediately forward of a trolley assembly as shown by line 11—11 in FIG. 9;

FIG. 12 is a vertical sectional view of the forward portion of a trolley assembly as seen along line 12—12 in FIG. 11;

FIGS. 13—19 illustrate the cathode loader;

FIG. 13 is a front view of the delivery unit and cathode loader as seen along line 13—13 in FIG. 1;

FIG. 14 is an elevation view of the apparatus opposite to FIG. 13;

FIG. 15 is a side view taken from the right in FIG. 14;

FIG. 16 is a top view of the apparatus in FIG. 14;

FIG. 17 is an enlarged fragmentary sectional view taken along line 17—17 in FIG. 16;

FIG. 18 is an enlarged fragmentary sectional view taken along line 18—18 in FIG. 16, including portions of the cathode conveyor;

FIG. 19 is an enlarged top view of the loader illustrating its operation and relation to the cathode conveyor;

FIG. 20 is an enlarged sectional view taken along line 20—20 in FIG. 13 through the delivery unit, illustrating its operation and further illustrating generally the features of the receiving unit similar to it;

FIG. 21 is an enlarged fragmentary sectional view taken along line 21—21 in FIG. 20;

FIG. 22 is a side elevation view of a transfer unit as seen generally along line 22—22 in FIG. 2, illustrating the operation of the unit and its relation to the delivery or receiving unit;

FIG. 23 is a plan view of the transfer unit shown in FIG. 22;

FIG. 24 is a side elevation of the transfer unit shown in FIG. 23;

FIG. 25 is a front view of the apparatus shown in FIG. 23 as viewed from the right;

FIGS. 26—31 show the sequence of operation of the loader in plan view;

FIGS. 32—37, respectively, illustrate the same sequence in side elevation;

FIGS. 38—47 illustrate the unloader and associated apparatus;

FIG. 38 is a front elevation of the receiving unit and unloader as seen along line 38—38 in FIG. 1;

FIG. 39 is an elevation view opposite to FIG. 38;

FIG. 40 is a side elevation of the apparatus as seen from the right in FIG. 38;

FIG. 41 is a plan view of the apparatus as shown in FIG. 38;

FIG. 42 is an enlarged vertical sectional view taken generally along line 42—42 in FIG. 41, showing the relation between the loader and the cathode conveyor;

FIG. 43 is an enlarged fragmentary sectional view taken along line 43—43 in FIG. 41;

FIG. 44 is a plan view of the unloader illustrating its relationship with the receiving unit and cathode conveyor and its operational positions;

FIG. 45 is a side view of the safety release apparatus shown along line 45—45 in FIG. 44 at an enlarged scale;

FIG. 46 is a view opposite to FIG. 45;

FIG. 47 is a plan view of the safety release apparatus as seen along line 47—47 in FIG. 40;

FIGS. 48—55 illustrate the operating sequence of the unloader in plan view; and

FIGS. 56—63, respectively, illustrate the same sequence of operation in side elevation.

PREFERRED EMBODIMENT OF THE INVENTION

General description

The stripping apparatus described herein relates to the recovery of metal in an electrolytic processing operation. In such an operation, metal such as zinc is electrolytically deposited on the side faces of reusable cathode assemblies in a cyclical process, each cathode assembly being subjected to the electrolytic deposition metal for a number of hours and then being stripped or relieved of the metal deposited on the cathode plate surfaces.

The cathode assembly handled by the described apparatus shall be designated generally herein by the numeral 10. The precise structure of the cathode assembly 10 is subject to modification, relative to the dimensions and materials used herein. However, such cathode assemblies generally will include a flat rectangular plate 11 (FIG. 3) and a supporting header bar 12 aligned across the plate 11 and projecting beyond both sides thereof. The header bar 12 serves as a structural supporting member for the depending plate 11, which is not otherwise supported during use. It also serves as an electrical conductor to carry current to the plate 11 in the cell circuit used during the deposition process. The cathode assemblies 10 shown in the drawings have protective coatings applied thereto along their side and top portions, this being preferably an insulating coating of resin. This coating, designated by the numeral 11a, serves as a physical

protector for the vulnerable portions of plate 11 and also serves to accurately define the area of exposed metal on plate 11 at which the metal being processed will be deposited.

The present apparatus is designated to supplant the stripping operation presently carried out by human means by a mechanized apparatus. The purpose of the apparatus is to remove the deposited metal from the side faces of each cathode plate 11 without the use of manual effort. The removed or stripped metal is then carried from the apparatus by a conveyor for further processing.

The apparatus disclosed herein comprises a combination of several mechanical elements which cooperate to automatically handle cathode assemblies during stripping of electrolytically deposited metal on the cathode plate side faces. The process by which metal is stripped or removed from the cathode plates using the apparatus disclosed herein is described generally in my copending application Ser. No. 636,797, filed May 8, 1967, for "Process for Stripping Metal from a Cathode." The process involves the subjection of the cathode and metal to high pressure water jets directed angularly toward the "solution line" or upper end of the deposited metal when the cathode assembly is suspended vertically by its header bar. Nozzles operating with working pressures between 4000—6000 p.s.i. and a flow rate of approximately ten gallons per minute of water are used in this process. The present disclosure relates to a fully automated assembly for handling the cathode units and mechanizing the stripping operation.

In the embodiment illustrated, the cathode assemblies 10 are intermittently delivered to the stripping unit in multiple groups, shown for illustration as being groups of seven cathode assemblies. Each group of seven cathode assemblies is carried to the unit on movable horizontal carrier arms 85 suspended from trolley assemblies 67 which are part of a supply conveyor 60. The supply conveyor 60 serves to move the trolley assemblies 67 from an exterior location (such as the cell room in which the metal is deposited on the cathode assemblies) to the stripping unit. It also serves to return the stripped cathode assemblies, again in groups of seven, back to the point of origin.

Each group of seven cathode assemblies is first stopped along the supply conveyor 60 at the location shown in the upper right hand corner of FIGURES 1 and 2. The guiding track at this section of the supply conveyor serves as a delivery transfer unit 107 movably mounted for lateral and vertical motion, to effect placement of the group of cathode assemblies on a walking beam assembly comprising a delivery unit 94a. The walking beam assembly serves as a metal-laden cathode delivery unit for a cathode loader 130 that individually places the cathode assemblies 10 on a cathode conveyor 15. The conveyor 15 longitudinally carries cathode assemblies 10 in line through the stripper enclosure 23 within which the hydraulic stripping operation described above is carried out. The exiting stripped cathodes are discharged from the cathode conveyor 15 by a cathode unloader 150 which places the individual cathode assemblies 10 on another walking beam unit that serves as a stripped cathode receiving unit 94b. It in turn accumulates a group of seven cathode assemblies 10 which are subsequently placed upon carrier arms 85 by a receiving transfer unit 107 that moves a carrier under the group of cathode assemblies and returns the loaded carrier to the main portion of the supply conveyor 60.

The basic section of the machine comprises: The cathode conveyor 15 which guides, supports and moves the individual cathodes through the stripping enclosure during the actual stripping process;

The stripper mechanism 19 comprising the enclosure, the manifolds, adjustable supports for the manifolds, various shields, guides and the receiving conveyor for the removed metal;

The supply conveyor 60 that carries the metal-laden cathode assemblies to the stripping unit and which receives the stripped cathode assemblies for return to an external source;

The two transfer units (part of the supply conveyor) which respectively deliver and receive the grouped cathode assemblies in relation to the supply conveyor, both of which are identical in structure, although their operative sequences are opposite;

The cathode delivery unit 94a and cathode received unit 94b which comprise basically identical walking beam assemblies operating in opposite directions for providing intermediate support and positioning to the plurality of cathode assemblies handled by the apparatus as a group;

The cathode loader 130 which combines with the delivery unit 94a to place individual cathode assemblies on the cathode conveyor;

And the cathode unloader 150 which combines with the receiving unit 94b to remove individual cathode assemblies from the cathode conveyor.

Each of these units will be described in detail below.

Cathode conveyor.—The cathode conveyor 15 can best be understood in relation to the remainder of the structure by reference to FIGS. 1 and 2. The conveyor 15 is an endless horizontal conveyor having an oval-shaped path. It carries the individual cathode assemblies 10 in-line through the stripper mechanism. The cathode conveyor 15 operates continuously during operation of the apparatus to feed consecutive cathode assemblies 10 from a delivery station, through the stripper mechanism 19 and to a receiving station where the stripped cathode assemblies are returned to the supply conveyor 60 described below.

The cathode conveyor 15 is movably supported on a fixed supporting I-beam 16 that defines the track for the conveyor assembly. Traveling within the rails of I-beam 16 and spaced evenly along a stripper conveyor chain 17 or a plurality of stripper conveyor guide wheels 18 (FIGS. 2, 8). Spaced at intervals along the lower edge of the stripper conveyor chain 17 are a number of cathode hangers 20. The cathode hangers 20 are of two types as shown in FIG. 3. Each pair of hangers 20 includes a lead hanger 20a and a trailing hanger 20b separated by a distance slightly greater than the width of a cathode plate 11 and less than the width of a header bar 12. The trailing hangers 20b extend slightly below the elevation of the lead hangers 20a and serve to trip a limit switch described below during operation of the apparatus. Each hanger 20 includes a coplanar upwardly facing ledge on which the header bars 12 are supported.

Power to drive the stripper conveyor assembly is provided by a conveyor motor 21 and driving sprocket 22 conventional for conveyors of this type.

The straight line operative portion of the cathode conveyor 15, which extends through and extends to both sides of the stripper mechanism 19, is shown at the top of FIG. 1 and at the right hand side of FIGS. 4 and 5. This section of the cathode conveyor 15 is the only section in which cathode assemblies 10 are handled on the hangers 20. To restrain movement of the cathode assemblies during such handling, fixed longitudinal rails 29 are rigidly mounted on the supporting framework in juxtaposition to the hangers 20 and the header bars 12 of the cathode assemblies carried thereby. The relation between these rails, the hangers 20 and the header bars 12 is illustrated in transverse section in FIG. 8. The rails 29 prevent disengagement of cathode along the operative portion of the cathode assembly 15 and further serve to provide vertical stability to the cathode assemblies during the actual removal of the deposited metal from the plates 11, as will be further described with relation to the operation of the stripper mechanism 19. The terminal portions of the rails 29 are illustrated and explained with respect to the cathode delivery unit 94a and the cathode loading unit 130.

Stripper mechanism.—The stripper mechanism 19 is shown in relation to the other devices in FIGS. 1 and 2

and is illustrated in greater detail in FIGS. 3 through 8. FIGS. 3, 4 and 5 show the stripper mechanism in its entirety and FIGS. 6, 7 and 8 illustrate the details of the hydraulic stripper apparatus.

The stripper mechanism is housed within a stripper enclosure 23, preferably fabricated of sheet metal with suitable reinforcing frame members. It is intersected by the operative flight of cathode conveyor 15, which carries the individual cathode assemblies 10 through the length of enclosure 23. As illustrated, both flights of cathode conveyor 15 pass through the enclosure 23, which is designed to be used with two cathode conveyors 15 if so desired. The return flight of the conveyor 15 is a single line system can return outside of enclosure 23 with equal efficiency.

The enclosure 23 has an entrance 24 (FIG. 4) and an exit (FIG. 5) through which the cathode assemblies 10 pass during their movement through the stripper mechanism 19. Both the entrance 24 and exit 25 are yieldably sealed by vertical rubber flaps 26 which extend toward the center line of the conveyor 15. Where the return flight of conveyor 15 also passes through enclosure 23, similar flaps 26 are provided to effectively seal the interior of enclosure 23 from the outside environment. The sealing of enclosure 23 is advisable due to the amount and pressure of water utilized within it during stripping of the metal. The enclosure 23 also is provided with a hinged transparent window 27 for access to the hydraulic stripping mechanism and for viewing the stripping process safely from outside the enclosure 23 (FIG. 3).

The hydraulic stripping mechanism shown in FIGS. 6-8 basically comprises a pair of transversely spaced manifolds 28 to which water is supplied under high pressure by an external pump (not shown). Each manifold 28 extends longitudinally along a short portion of the cathode conveyor 15. Each is identically supported, one side of the hydraulic stripper mechanism being a mirror image of the other. The following description, relating to a single side of the apparatus, will be seen to be equally applicable to the opposite or remaining side thereof.

The manifold 28 is pivotally mounted about a longitudinal horizontal axis relative to conveyor 15 by a support bracket 30. The manifold 28 is angularly adjustable relative to the support bracket 30 by means of a vernier angular adjustment apparatus 31 fixed to the bracket 30, having accurate gearing by which the manifold 28 can be angularly adjusted and held in place. The manifold 28 is supported on the bracket 30 by means of bearings 32, which define its longitudinal axis of rotation.

The support bracket 30 is vertically adjustable relative to a frame 33. Frame 33 at each side of the mechanism is slidably mounted for transverse positioning relative to transverse braces 42 which are fixed as part of the framework of enclosure 23. The frame 33 is locked in place relative to the braces 42 by locking bolts 44 which are received through transverse slots 52 (FIG. 8) that permit such transverse adjustment. The actual adjustment is controlled by adjustment screws 53 (FIGS. 6 and 7) which are received by collars 43 on a fixed support plate 41 fixed relative to the braces 42. The screws 53 threadedly engage ears 54 which extend inward from the upper portion of the respective frames 33. By turning the screws 53, the two frames 33 are moved toward or away from the center line of the cathode conveyor 15 in unison.

Vertical positioning of manifold 28 is provided by means of lifting pins 35 which extend from the support bracket 30 to a transverse bracket 36 vertically positioned by an upright screw 37 held in place by adjusting and locking nuts 38 (FIG. 8). The connection between the upper ends of the pins 35 and the transverse support 36 is transversely slotted and open to accommodate the transverse movement possible between the frame 33 and the bracket 36.

As shown, each manifold 28 is provided with two longitudinally spaced hydraulic nozzles 45 directed angularly downward toward the vertical center line extending

through the cathode conveyor 15. The relation between these elements and a cathode plate 11 having deposited metal 48 on each side is illustrated in FIG. 8. The jet or stream of water released from the nozzles 45 should preferably be aimed at or slightly above the "solution line" or upper edge of the deposited metal 48. Interposed between the two hydraulic nozzles 45 on each manifold 28 is a pneumatic nozzle 46 to assist in the stripping operation. It has been found that the use of compressible air in addition to the noncompressible water serves to facilitate the ballooning of the metal 48 as it is peeled or stripped from the cathode plates 11, and helps to insure proper stripping of the metal 48 along the entire height of the cathode plate 11.

As shown, the stripped metal sheets from both sides of the cathode plates 11 are fed by fixed guides 55 in the enclosure 23 to the upper flight of a horizontal belt conveyor 50. The conveyor 50 extends longitudinally outward beyond enclosure 23 and serves as a delivery belt for the stripped metal. The water that is used in the stripping process flows to the bottom of enclosure 23 and is recovered from a lower sump (not shown).

Supply conveyor.—The supply conveyor 60 is partly shown in FIGS. 1 and 2 along the portions thereof adjacent to the stripping apparatus. The supply conveyor 60 is built upon a conventional chain conveyor apparatus and is used to convey carriers which support grouped cathode assemblies during movement between the stripper mechanism and the cell room or other intermediate storage facility.

The supply conveyor 60 consists of an I-beam 61 suitably attached to a support framework (not shown). The conveyor 60 is best seen in FIG. 9, the trolley mechanism utilized in conjunction with the supply conveyor 60 being shown in greater detail in FIGS. 11 and 12. The conveyor includes a continuous moving chain 62 suspended in conventional fashion by conveyor guide wheels 63 spaced along the chain 62 and rolling within the rails of the I-beam 61.

Also supported on the framework are channel rails 64 in which the conveyor trolley is guided. The rails 64 are located immediately below the I-beam 61. Evenly spaced along the constantly moving chain 62 are pusher blocks 65 which depend downwardly from the chain 62 and which releasably engage the individual trolley assemblies 67 to space the trolley assemblies and move them with the conveyor chain 62. Power for motion of the conveyor chain 62 is provided by a conventional motor driven apparatus indicated generally as the drive unit 66 shown in FIG. 1.

The trolley assembly used in conjunction with the supply conveyor 60 is illustrated in FIGS. 9, 11 and 12. It is generally designated by the numeral 67. Each trolley assembly 67 is suspended from the channel rails 64 by front and rear sets of support wheels 68. Horizontal guide wheels 70 prevent transverse movement of the trolley assembly 67 between channel rails 64. A pivoted load dog 71 is situated at the upper portion of each trolley assembly 67 to engage the pusher blocks 65 on the conveyor chain 62 to selectively advance the trolley assemblies in the direction indicated by arrow A in FIG. 12.

A reverse load dog 72 is provided on each trolley assembly 67. The reverse load dog 72 is used in the event that the trolley assembly 67 is disengaged from chain 62 while on an upward incline. If this should occur, the lower portion of the reverse load dog 72, designated by numeral 74, will engage the lower flange of the channel rail 64 to prevent reverse movement of the trolley assembly 67.

During the operation of the stripping sequence, it is necessary to locate and hold the individual trolley assemblies stationary. This is accomplished by the structure shown in FIG. 12. Situated beneath the lower end of the load dog 71 and extending forward of the trolley assembly 67 is a disengaging arm 77. The arm 77 is free to rotate in a clockwise direction about a pivot shaft 78 in

on the trolley assembly 67 when engaged by an accumulator element as described below. Such pivotal movement will cause the upper end of the disengaging arm 77 to be released from normal contact with the load dog 71. The normal operating position of the elements is as shown in FIG. 12, with the outer flat end 79 of the arm 77 being in mating surface to surface contact with a complementary flat surface 80 on the load dog 71. The disengaging arm 77 is maintained normally in this position due to gravitational forces on the front end thereof. However, when the forward end of the arm 77 is lifted, the load dog 71 is freed from the upright position shown, and will pivot about its supporting transverse shaft 75 in a counterclockwise direction as seen in FIG. 12. This effectively disengages the trolley assembly 67 from the conveyor chain 62. Subsequent counterclockwise pivotal movement of the arm 77 will reengage the load dog 71 and resume motion of the trolley assembly 67 when the load dog 71 is again abutted by a pusher block 65.

The rear end of each trolley assembly 67 is provided with a rearwardly extending stop 81, which functions to engage the arm 77 of a following trolley when a series of trolley assemblies are accumulated at any location along the supply conveyor 60.

The carrier for a series of cathode assemblies 10 is best seen in FIGS. 9 and 22. Attached to the lower portion of each trolley assembly 67 is a load bar 82. The front and rear vertical connections for the load bar 82 permit free pivotal movement to accommodate curves in the track mechanism. Suspended from the load bar 82 is a vertical shaft 83 to which is attached a depending carrier frame 84. The frame 84 includes longitudinally spaced carrier arms 85 having an upwardly facing notched edge surface adapted to hold a series of seven cathode assemblies by engagement beneath the respective header bars 12. The manner of suspending the cathode assemblies 10 and spacing them on the carrier arms 85 is believed to be evident from the disclosure of FIGS. 9 and 22.

The accumulator mechanism used in conjunction with the supply conveyor 60 is shown in several of the drawings in conjunction with other mechanisms. Attention is directed particularly to FIGS. 9, 10 and 23 through 25. The accumulator assembly is generally designated by the numeral 86. Two types of accumulators are shown—transfer accumulators 86a and surge accumulators 86b. They differ only in function and are structurally identical. The following description is equally applicable to each.

As seen in FIGS. 9 and 10, the accumulator assembly 86 is rigidly mounted at one side of the channel rails 64 by an accumulator mount 87. Attached to the accumulator mount 87 is a cylinder mount 88 to which is attached an actuating cylinder 89. The outer end of the piston rod included in the actuating cylinder 89 is pivotally connected to a disengaging cam arm 90 by means of a connecting pin 91. Attached to the disengaging cam arm 90 is a disengaging cam 92.

FIG. 25 illustrates the inactive position of the accumulators 86. FIG. 9 illustrates the actuated position of the accumulators 86. When actuated, the cylinder 89 rotates the horizontally positioned disengaging cam arm 90 counterclockwise as shown in the drawings on a pivot pin 93 to a position perpendicular to the channel rail 64 on which it is mounted. At this position, the cam 92 intersects the path of an oncoming arm 77 of a trolley assembly 67, causing the trolley assembly 67 to become disengaged from the moving conveyor chain mechanism. Release of the actuating cylinder 89 returns the cam 92 to its position clear of the path of the moving trolley.

Delivery and receiving units.—As seen in FIG. 1, the stripping apparatus includes a delivery unit and a receiving unit for the grouped cathodes which are respectively delivered from the supply conveyor 60 prior to stripping or area discharged from the conveyor 60 following the stripping operation. The delivery unit is designated by the numeral 94a in FIGS. 1 and 2, the receiving unit being

designated by the numeral 94b. While their operations are somewhat different and will be described in detail in connection with the respective loading and unloading units for the individual cathode assemblies, the basic mechanism used in each is identical and will be described in detail here, it being understood that this description is equally applicable to either unit.

The details of the structure can best be seen in FIGS. 13-16, 20 and 21. The apparatus constitutes a walking beam assembly including a pair of static load bars 95 fixed to a pair of static load bar support members 96. The spacing between the static load bars 95 is such as to permit the transfer of cathode assemblies 10 from the previously described carrier arms 85 to the static load bars 95. The upper edges of the static load bars 95 are notched to maintain the spacing between the cathode assemblies 10 in a condition identical to the spacing thereof when suspended from the carrier arms 85. Located inside the static load bars 95 are parallel dynamic load bars 97 which are respectively supported by a dynamic load bar support platform 98.

The interrelation between the static load bars 95 and the dynamic load bars 97 can best be seen from FIG. 20. The platform 98, which supports the dynamic load bars 97, is moved eccentrically as indicated by the dashed lines in FIG. 20. The platform 98 is suspended by eccentric stud shafts 100 rotatably received within bearings 101 on the outer side walls of the platform 98. The stub shafts 100 are turned about the axis of transverse drive shafts 102 rotatably carried by a fixed framework support 106. The shafts 102 are rotated by means of chains 103 powered by a motor and clutch-brake unit designated generally by the numeral 104.

An additional feature of the walking beam apparatus is a plate snubber 105 which moves with the platform 98 and which extends across the grouped cathodes to engage the lower corners of each plate when the dynamic load bars 97 are raised above the static load bars 95. The plates 11 of the cathode assemblies 10 therefore are prevented from swinging with the eccentric movement imparted to the cathode assemblies by the dynamic load bars 97.

Each revolution of the drive shafts 102 causes the dynamic load bars 97 to advance the cathode assemblies 10 on the static load bars by a distance equal to the separation between one notch on the upper surface thereof. Depending upon whether the cathode assemblies are being advanced to the left or to the right as seen in FIG. 20, the apparatus will be utilized to either feed the cathode assemblies 10 individually at the left end of the static load bars 95 or will be used to accumulate a group of cathodes across the static load bars prior to receiving of the group by the supply conveyor 60. These details will be further evident from the description below with respect to the loading and unloading mechanisms for the cathode conveyor 15.

Transfer units.—As shown in FIG. 1, the apparatus for delivering and receiving the cathodes includes two structurally identical transfer units designated generally by the numeral 107, which serve to transfer a group of cathode assemblies 10 from the supply conveyor 60 to the static load bars 95 of the delivery unit 94a and to transfer a group of cathode assemblies 10 from the static load bars 95 of the receiving unit 94b to the supply conveyor 60 after completion of the stripping operation. The structure of the two units is illustrated in detail in FIGS. 22-25, and the minor modifications in control elements and operation which relate to the specific application of the structure in each instance will be described in detail below with reference to the loader and unloader assemblies.

The apparatus, as can be seen in FIG. 22, is concerned with the transfer of position of movable track sections 110, which in its normal position is simply an extension of the two channel rails 64. The movable track sections 110 carry a transfer accumulator 86a, shown at the left

in FIG. 25. Accumulator 86a locates a carrier frame 84 on the movable track sections 110, and serves to disconnect the carrier frame trolley assembly from the constantly moving conveyor chain of the supply conveyor 60. A surge accumulator 86b is mounted on the channel rails 64 adjacent to the incoming end of the movable track sections 110 to hold succeeding carrier frames and trolleys from entering the movable track sections.

The movable track sections 110 are structurally supported by a movable frame 116, which has an open rectangular configuration to permit vertical and horizontal movement of the track sections 110 while circumventing the stationary and I-beam 61 of the supply conveyor 60. I-beam 61 is illustrated in FIGS. 23-25, although the remaining portions of the supply conveyor elements are not illustrated. In FIG. 22, the supply conveyor elements are shown, along with a carrier frame 84 and the suspended cathode assemblies 10 carried thereby. FIG. 22 illustrates in dashed lines the ultimate horizontal and vertical extension of the frame 116 and movable track section 110, the normal position of the track sections 110 in longitudinal alignment with the channel rails 64 being shown in full lines.

The transfer unit 107 is movably supported on a fixed mounting framework including longitudinal structural members 108. A pair of transverse horizontal guides 111 in the form of cylindrical rods are fixed between the members 108 by suitable mounting flanges 112. A horizontal carriage 119 is supported on the horizontal guides 111 by means of integral collars 115. The normally exposed portions of the guides 111 are protected from external corrosion by guide boots 114.

The frame 116 is mounted for vertical movement relative to the horizontal carriage 119 by means of upstanding vertical guide rods 118 fixed to the upper portion of the frame 116 and slidably received within suitable bushings 120 in the horizontal carriage 119.

Horizontal movement is imparted to the horizontal carriage 119 by means of a horizontal cylinder assembly 113, having its base anchored to one member 108 and having the outer end of its piston rod connected to the horizontal carriage 119. Vertical movement is imparted to the frame 116 relative to the horizontal carriage 119 by means of a vertical cylinder assembly 117, the base of which is fixed to the horizontal carriage 119. The outer end of the piston rod of the cylinder assembly 117 is connected to the upper portion of the movable track frame 116.

The movement imparted by the cylinder assemblies 113, 117 to the movable track frame 116 and track sections 110 is a succession of motion downward, forward, upward and rearward, the exact sequence being dependent upon the particular application of the apparatus as will be described below. By such movement, a group of cathodes can be either placed downwardly on the static load bars 95 of one of the units 94 or can be lifted from the static load bars as might be required.

During the various movements of the transfer units 107, it is likely to become misaligned with relation to the stationary channel rails 64. To eliminate such misalignment, track aligners are included in the apparatus. In FIG. 25 can be seen vertical alignment bars 121 fixed to the upper surfaces of the channel rails 64 and overlapping the upper surfaces of the movable track sections 110 when in their normal position as a portion of the supply conveyor 60. Also included are overlapping horizontal alignment elements 122 and 123, fixed respectively to the movable track sections 110 and the channel rails 64, which serve to properly position the movable track sections 110 in correct alignment as extensions of the channel rails 64 each time the movable track sections 110 are repositioned in their normal locations.

Cathode loader.—The stripping machine loader (FIGS. 13-19) picks up cathode assemblies 10 individually from the delivery unit 94a and places them on the hangers 20 of the cathode conveyor 15. The loader is generally

designated by the numeral 130 and can be seen in FIGS. 1 and 2 in relation to the other elements of the apparatus.

The operative portion of the loader that actually engages the header bars of the cathode assemblies constitutes a pair of load dogs 131 which extend transversely from a longitudinal support 132 aligned parallel with the cathode conveyor 15. The load dogs 131 are located at the upper portion of the stripping machine loader 130 as shown in the drawings. They are positioned by means of a longitudinal alignment assembly 133 and a transverse alignment assembly 138 which respectively account for the longitudinal and transverse movement of the load dogs 131 necessary for their proper operation. Their upper surfaces intersect a plane across the intermediate elevation of the adjacent dynamic load bars 97 of delivery unit 94a.

As shown in FIG. 18, the longitudinal alignment assembly 133 comprises a longitudinal alignment guide frame 134 which rides on vertical support bearings 135 and a pair of horizontal guide bearings 136. The longitudinal alignment guide frame 134 is therefore movably mounted relative to an alignment support member 137.

The longitudinal alignment support 137 in turn is mounted on a transverse alignment assembly 138. The transverse alignment assembly 138 is basically identical to the longitudinal alignment assembly 133, but is oriented perpendicular to the direction of movement of the cathode conveyor 15. The transverse alignment assembly 138 includes a transverse guide frame 140 which rides on vertical support bearings 141 and a pair of horizontal guide bearings 142. The transverse alignment guide frame 140 is therefore movably mounted relative to a transverse alignment support 143. Support 143 in turn is fixed relative to a stationary frame member 146 which provides a fixed reference support for the cathode loader 130 relative to the other elements of the stripping operation.

Horizontal movement of the longitudinal alignment assembly 133 is imparted through the load dogs 131, the trailing hangers 20b being used to abut the trailing load dog 131 in the direction of movement of the cathode conveyor 15. Return of the load dogs 131 to an initial position between the static load bars of the delivery unit 94 is accomplished by means of a horizontal return cylinder 144 (FIG. 17) connected between the longitudinal alignment support 137 and a projecting end plate 147 fixed to the movable longitudinal alignment guide frame 134.

Transverse movement of the load dogs 131 relative to the cathode conveyor 15 is accomplished by actuation of a double acting cylinder assembly 145 connected between the transverse alignment support member 143 and an end plate 148 fixed to the transverse guide frame 140. The cylinder 145 moves the load dog 131 from a position clear of the hangers 20 on the cathode conveyor 15 to a position that lies partially under the inmost notch of the extended dynamic load bars 97 of the adjacent delivery unit 94. In FIG. 19 is illustrated the normal non-operative position of the cathode loader 130 (full lines) and the extreme position of the loader 130 immediately prior to retraction of load dog 131 after placement of a cathode assembly 10 on the cathode conveyor 15 (dashed lines).

Cathode unloader.—The cathode unloader, generally designated by the numeral 150, reassembles the cathode assemblies 10 in a group of seven for replacement to the supply conveyor 60. The stripped cathodes will then be returned to the cell lines for reuse.

The cathode unloader 150 is structurally similar to the cathode loader 130. However, since the deposited metal has been removed, vacuum cups on the plan plate surfaces can be effectively used to grasp the cathode assemblies positively and carry them to their intended receiving position on the receiving unit 94b.

The cathode unloader 150 comprises a vacuum engagement assembly 151 mounted at the upper portion of the

unloader 150. The vacuum engagement assembly 151 includes a set of four vacuum cups 152 attached to a vacuum cup support frame 153 by four horizontal vacuum support rods 154. The rods 154 are spring biased by compression springs 155 to provide yieldable engagement of the cathode plates 11 by the vacuum cups 152. This permits the vacuum cups 152 to solidly engage the cathode plates without knocking the cathode assembly from the cathode conveyor hangers 20. The rods 154 are located by springs 155 and motion limiting nuts 156 at the ends of the rods 154 opposite to the vacuum cups 152. Vacuum cups 152 are alternately connected to a conventional vacuum pump or to a positive pump for grasping cathode plates or releasing them respectively.

The vacuum engaging assembly 151 is supported on a vacuum cup support frame mount 157. That portion of the cathode unloader 150 that advances the vacuum engagement assembly 151 transversely relative to cathode conveyor 15 to a location where the cathode plate 11 engaged by it is removed from the cathode hangers 20 is designated herein as the engagement alignment assembly, indicated generally by the numeral 158. The engagement alignment assembly 158 comprises an engagement alignment housing 160 including an engagement alignment guide frame 161. The engagement alignment guide frame 161 rides on a pair of vertical support bearings 162 and a horizontal guide bearing 163. The engagement alignment guide frame 161 travels relative to an engagement alignment support 164 which mounts the bearings 162 and 163.

The engagement alignment support 164 in turn is mounted for longitudinal movement relative to the cathode conveyor 15. It is carried at the upper portion of a feeder assembly shown generally by the numeral 165. The feeder assembly 165 comprises a feeder housing 166 containing a feeder alignment frame 167. The feeder alignment frame 167 travels with respect to a feeder support frame 168, being guided by vertical support bearings 170 and a horizontal guide bearing 171.

The engagement alignment assembly 158 that carries the vacuum engaging assembly 151 is moved parallel to the cathode conveyor 15 by means of an engagement alignment actuating cylinder 172 located immediately below the engagement alignment assembly 158 and connected between the support 164 and frame 161. Movement of the vacuum cups 152 parallel to the cathode conveyor 15 is accomplished by a second longitudinal cylinder 173 connected between the feeder alignment frame 167 and its supporting frame 168. The positions and connections between the cylinder 172, 173 are best seen in FIGS. 42 and 43. FIG. 44 illustrates in full lines the normal position of the inoperative cathode unloader 150 and shows in dashed lines the extreme position of the vacuum cups at the moment of placement of a cathode assembly 10 on the dynamic load bars 97 of the receiving unit 94b.

Immediately adjacent to the cathode unloader 150 in the direction of movement of the cathode conveyor 15 is a motion limiting gate comprising a striking plate 174 that intersects the path of the cathode assemblies 10 which might still be retained on the hangers 20 after passing the unloader 150. The striking plate 174 is part of an escape gate assembly generally designated by the numeral 175 and illustrated in FIGS. 44 through 47 in particular. It permits cathodes to pass this area unharmed while also serving to shut down the associated apparatus until the malfunction has been corrected. This prevents damage to the rather expensive cathode assemblies 10 and insures a safety device to automatically detect a malfunction that would permit the cathode assemblies to pass the unloader station.

The striking plate 174 is mounted on an upright support member 176. The member 176 in turn pivots on a hinged support 177. In normal operation, the upright support member 176 is held in a fixed position intersecting

the area immediately below the capital conveyor 15 by an escape gate actuating cylinder 178. If the plate 174 is contacted by a moving cathode assembly, a control element is actuated to operate the cylinder 178 and cause it to release the upright support member 176 so that it may swing out of the way to permit the cathode to pass. The plate 174 and support member 176 are then free to swing and will offer no further resistance to movement of a cathode plate. The control element, shown in FIGS. 44 and 46 particularly, is illustrated as a switch 210 mounted on the member 176 immediately behind the striking plate 174. Conventional controls are utilized to actuate the cylinder 178 when the switch 210 is placed in operation. Interrelated controls connected with switch 210 are preferably used also to shut down the cathode conveyor 15 and the hydraulic pump for the stripper mechanism 19. This effectively shuts down the entire operation until the malfunction can be corrected and eliminates to a large extent the necessity for manual observation of the machinery during use.

Operation of the apparatus.—The following discussion of the operation of the various components detailed above shall also serve as a description of the control elements that sequence the apparatus automatically. These control elements will be described with relation to the detail drawings and the schematic view of the operation of the loader and unloader for the cathode conveyor. Directions of movement shall be described in relation to the longitudinal movement of the cathode conveyor 15 along the working flight that extends through the stripper mechanism. The controls used to sequence the functions of the apparatus can be either electrical, pneumatic or a combination of both systems, as might be desired. The designation "switch" as used herein shall be understood to refer equally to an electrical control element or a pneumatic control element. The control elements themselves and the general nature of the control circuitry is conventional and it is only the unique application of these control elements to the physical structure that concerns this disclosure.

Operation of the first transfer unit.—As described above, the transfer units 107 serve to deliver groups of cathodes to the delivery unit 94a and to return groups of cathode assemblies from the receiving unit 94b. The two transfer units 107 operate in a manner generally similar, and reference herein will be made to FIGS. 22-25 to illustrate the operation of each unit.

The general function of the first transfer unit 107 is to interrupt the otherwise constant movement of carrier trolley assemblies 67 along the channel rails 64, to swing a load of cathode assemblies on a single carrier over the static load bars 95 of the delivery unit 94a and to lower the cathode assemblies 10 onto the receiving notched upper edges of the static load bars 95.

The static load bars 95 are provided with excess notches so as to be capable of holding more cathode assemblies than required by the normal operation of the delivery unit 94a. A switch 180 on one of the static load bars 95 (FIG. 22) is energized when the last cathode assembly 10 from a group of such assemblies passes to the left towards the cathode conveyor 15, indicating that the required number of empty spaces are available at the rear of the static load bars 95. A second switch 181 is located on the movable track sections 110 adjacent to the transfer accumulator 86a mounted thereon. Switch 181 is actuated by a trolley assembly 67 in place against the accumulator 86a.

The actuation of switches 180 and 181 initiate the operating sequence of the transfer unit 107. This initial actuation initiates horizontal movement of the movable track section 110 by actuation of the horizontal cylinder assembly 113 to move the structure above the delivery unit 94a. When the horizontal movement has been completed, a switch 182 on the adjacent transfer assembly mount 108 is actuated, which controls the hoist cylinder

assembly 117 and initiates downward movement of the movable track sections 110. The downward of the track sections 110 continues until switch 183 located on the I-beam 61 is contacted by the upper portion of the movable track frame 116 (FIG. 24), which indicates that the lowering sequence has been completed. When switch 183 is actuated, the carrier arms 85 will have discharged the cathode assemblies 10 onto the static lead bars 95 as shown in dashed lines in FIG. 22. The side edges of the grouped cathode assemblies 10 are engaged by a yieldable guide 202 on delivery unit 94a for alignment purposes.

Actuation of switch 183 operates the horizontal cylinder assembly 113 to return the horizontal carriage 119 to its original position. When this occurs, switch 184 (FIG. 23) is actuated, which then operates the hoist cylinder assembly 117 to raise the frame 116 and center the movable track sections 110 in normal alignment with the channel rails 64. Movement of the track sections 110 is completed when the frame 116 contacts a final indicating switch 185 on the horizontal carriage 119, switch 185 being utilized to release the transfer accumulator 86a and permit the unloaded trolley and carriage to pass from the movable track sections 110.

Release of the transfer accumulator 86a causes a switch 186 to be actuated by contact with the cam arm 90. This releases the surge accumulator 86b and allows the next load of cathode assemblies on a carrier to enter the transfer unit 107. Entry of the unit is indicated by the tripping of a switch 187 adjacent to the surge accumulator 86b, switch 187 being actuated by contact of the incoming trolley assembly 67. Switch 187 actuates the transfer accumulator 86a to insure that the incoming carrier will be properly stopped. The actuation of accumulator 86a causes cylinder 89 of the accumulator to pivot, releasing contact with a switch 188 on the movable track sections. Switch 188 actuates the surge accumulator 86b and prevents two carriages from entering the movable track sections 110 at any time. The final entry of the trolley against the transfer accumulator 86a serves to disengage the trolley assembly from the conveyor chain 62 and pusher block 65, and also serves to actuate switch 181, so that the entire sequence will again be repeated when the previously described switch 180 on the delivery unit 94a is again actuated.

Loader operation.—Loading of the cathode assemblies onto the hangers 20 of the cathode conveyor 15 is interrelated with the operation of the delivery unit 94a, which successively feeds the individual cathode assemblies 10 into proper position for loading. Operation of the loader can best be seen in the schematic drawings, FIGS. 26-37. The various switches and control mechanisms are also illustrated in FIGS. 13-19 so far as possible.

The loading sequence can be described best as a series of steps as follows:

Sequence #1 (FIGS. 26, 32).—This is the normal rest position of the loader 130. A cathode assembly 10 is in position at the adjacent notches of the static load bars 95 on the delivery unit 94a. The load dogs 131 are retracted and in a longitudinal position at their rearmost location relative to the direction of movement of the cathode conveyor 15.

Sequence #2 (FIGS. 27, 33).—The trailing hanger 20b of the cathode conveyor 15 engages a switch 190 on the supporting framework to initiate the loader movement. The switch 190 is not engaged by the lead hanger 20, which is slightly shorter than the trailing hangers 20b so as to clear switch 190. Actuation of switch 190 releases pressure on the feeder return cylinder 44, so that the load dogs 131 and longitudinal support assembly 133 are free to move in the direction of movement of the cathode conveyor 15. It also operates the pickup actuating cylinder 145 to extend the transverse support assembly 148 and move the outer ends of the load dogs 131 beyond the center line of movement of the hangers 20.

Sequence #3 (FIGS. 28, 34).—Actuation of switch 190 also serves to operate a time delay control for the motor and clutch-brake unit 104 of the delivery unit 94a. After the load dogs 131 have had time to reach their fully extended position, the unit 104 is actuated to move the dynamic load bars 97 and step the cathode assemblies 10 one notch along the static load bars 95. Platform 98 gyrates as shown by arrow B in FIG. 20. The adjacent cathode assembly 10 is thereby placed upon the upper surfaces of the load dogs 131. The brake in the unit 104 stops the movement of the dynamic load bars 97 at their original position following one revolution of the drive shafts 102. At this position, the dynamic load bars 97 are again retracted below the static load bars 95.

Sequence #4 (FIGS. 29, 35).—The continuing movement of the cathode conveyor 15 brings the trailing hanger 20b into physical contact with the rear load dog 131 and begins to push the load dogs and the longitudinal support assembly 133 in the direction of movement of cathode conveyor 15. The load dogs 131 thereby move at the same speed as the hangers 20.

Sequence #5 (FIGS. 30, 36).—As the longitudinal support assembly 133 moves with the cathode conveyor 15, a switch 191 on the alignment support 137 is actuated. Switch 191 reverses the connections to the pick up actuating cylinder 145 and retracts the transverse support assembly 138, thereby also retracting the load dogs 131. This pulls the load dogs 131 clear of the header bar 12 which rested upon it, the header bar 12 being pulled against the hangers 20 and now being supported by the coplanar ledges thereof. At this time, the cathode assembly 10 is entering the retaining area of the cathode conveyor 15 between the rails 29, which prevents disengagement of the cathode assembly 10 from the hangers 20.

Sequence #6 (FIGS. 31, 37).—As the pickup alignment 140 moves to the fully retracted position, a time delay relay initiated by switch 181 is actuated to provide pressure to the feeder return cylinder 144 moving the longitudinal support assembly 133 in a direction opposite to the direction of movement of the cathode conveyor 15. The apparatus is therefore returned to the initial position shown in FIGS. 26 and 32.

Stripper operation.—The operation of the stripper mechanism is believed to be generally evident from the previous description of the structure involved. However, referring to FIGS. 3-8, the individual cathode assemblies 10 enter the stripper enclosure 23 through the entrance 24, the yieldable rubber flaps 26 permitting such entry while generally sealing the opening. Within the stripper enclosure 23 water under high pressure is continuously supplied to the hydraulic nozzles 45 through manifolds 28 from an external pump (not shown). In addition, the pneumatic nozzles 46 interposed between the hydraulic nozzles 45 are also provided with high pressure air from an external source. As the individual cathode assemblies 10 travel past the nozzles 45 the deposited metal 48 (FIG. 8) is first loosened at the upper end or "solution line" and is progressively released from the flat cathode plate 11 along the entire length thereof. The released metal falls between the guides 55 and is received on the conveyor belt 50 for discharge and further handling operations.

Cathode unloader.—The operation of the unloader is best illustrated in the schematic drawings, FIGS. 48-63. The operating controls are also illustrated so far as possible in FIGS. 38-47. The sequence of operation involves the following successive steps:

Sequence #1 (FIGS. 48, 56).—The initial position of the unloader has the vacuum engaging assembly 151 in a rearward position relative to the position of movement of the cathode conveyor 15 and the vacuum engaging assembly 151 and vacuum cups are retracted beyond the center line of conveyor 15. An incoming cathode assembly 10 is on the hangers 20 of conveyor 15 approaching the unloaded station downstream of the stripper mechanism 19.

At this location, the cathode assembly begins to clear the outermost ends of the retaining rails 29.

Sequence #2 (FIGS. 49, 57).—The incoming front edge of the cathode plate 11 strikes a switch 192 mounted on the supporting framework across the path of the cathode assembly 10. Switch 192 operates a relay to actuate the controlling valve for cylinder 172 which moves the vacuum engaging assembly to an extended position causing the vacuum cups 152 to engage the plate of the cathode assembly 10. Switch 192 also initiates the application of vacuum pressure to the cups 152 so as to grasp the smooth cathode plate.

Sequence #3 (FIGS. 50, 58).—The vacuum engaging assembly 151 continues its movement to an extended position, the cups 152 traveling beyond the center line of the cathode conveyor 15. The cathode assembly 10 grasped by the cups 152 is thereby removed from hangers 20 and suspended solely by the vacuum cups 152. At this time, the cathode assembly 10 clears switch 192, shutting off the vacuum pump, but still maintaining vacuum pressure at cups 152.

Sequence #4 (FIGS. 51, 59).—With the vacuum engagement assembly 151 completely extended, a switch 193 mounted between the cylinder 172 and the support frame 161 for the vacuum cups 152 is actuated to indicate the complete extension of vacuum engaging assembly 151. Switch 193 actuates a control mechanism to operate cylinder 173, causing the vacuum engaging assembly 151 to be moved in the direction of movement of cathode conveyor 15 to a position centered between the dynamic load bars 95 of the receiving unit 94b.

Sequence #5 (FIGS. 52, 60).—When the cathode assembly 10 is properly centered with respect to the receiving unit 94b, a switch 194 is contacted by the cathode plate and is thereby actuated. Switch 194 actuates the motor and clutch-brake unit 104 of the receiving unit 94b, causing platform 98 thereof to rotate in a clockwise direction as indicated by arrow A in FIG. 20. The two dynamic load bars 97 move outward beneath the suspended cathode assembly 10 and the outermost notches thereof are engaged beneath the extended portions of the header bar 12.

Sequence #6 (FIGS. 53, 61).—A timing relay, originally activated by contact of switch 194, now energizes a valve to feed compressed air from an external source to the vacuum cups 152. The compressed air blows the cathode assembly 10 free of the cups 152 in a positive manner, so that the cathode assembly 10 is now supported solely by the dynamic load bars 97.

Sequence #7 (FIGS. 54, 62).—A timing relay also initiated by actuation of switch 194 now reverses the connections to the cylinder 172, causing the vacuum engaging assembly to be retracted. The dynamic load bars 97 continue their eccentric movement, placing the cathode assembly 10 on the closest notches of the static load bars 95 and advancing previously placed cathode assembly 10 one notch across the load bars 95.

Sequence #8 (FIGS. 55, 63).—The final operation is also accomplished by a timed relay actuated by the switch 194. It reverses the connections to the cylinder 173 to return the vacuum engaging assembly 151 in a direction opposite to the direction of movement of cathode conveyor 15. The apparatus is therefore returned to its original position in preparation for the next cathode that is approaching switch 192.

Operation of second transfer unit.—The operation of the second transfer unit 107 that returns a group of stripped cathode assemblies to the supply conveyor 60 is very similar to the operations described with respect to the first transfer unit. The control devices involved in addition to or in place of those previously described are also indicated in FIGS. 22-25.

One of the static load bars 95 of the receiving unit 94 is provided with a header bar detector switch 195 (FIG.

20) that indicates the presence of a cathode assembly 10 at the notch adjacent to its latch notch at the end thereof opposite to the cathode conveyor 15. The presence of a cathode assembly at this position normally indicates that a full group of cathode assemblies is in position for lifting. A safety switch 196 is provided on the final notch, to indicate malfunction of the apparatus. If the cathode plates 10 are shifted an additional step so that the switch 196 is closed, this indicates that the transfer unit 107 has failed in some manner to lift the group of cathode 10 assemblies and switch 196 serves to shut down the apparatus until the malfunction is corrected.

Closure of switch 195 initiates the operation of transfer unit 107. However, prior to this, the movable track section 110 will have received a trolley assembly 67 and 15 the carrier suspended therefrom. The required operations of the transfer accumulator 86a and surge accumulator 86b and the associated switches that control receipt of the trolley assembly 67 are identical to the steps previously described above with respect to the first transfer 20 unit 107.

Actuation of switch 195 serves first to operate the hoist cylinder assembly 117 to lower the movable track section 110 and the carrier beneath it. When the carrier arms 85 have reached their lowermost positions, below the elevation of the static load bars 95 of the receiving unit 94b, switch 183 (FIG. 24) will be actuated, to activate the horizontal cylinder assembly 113 and move the carrier arms beneath the collected group of cathodes on the receiving unit 94b. Movement of the horizontal cylinder assembly 113 will terminate on actuation of switch 182 (FIG. 23). At this time, the carrier arms 85 will be properly centered beneath the collected group of cathode assemblies 10. Their position will be as shown in dashed lines in FIG. 22.

To assure proper alignment, a stationary guide is provided above the platform 98 of the receiving unit 94b. This guide, designated by numeral 200 can be best seen in FIGS. 38-41. It is supported on the stationary framework by post 201. Guide 200 is adapted to be engaged by the rear edges and side surfaces of the carrier arms 85 as the arms are moved downward into position above platform 98. This serves to stabilize the carrier and assure its proper position under the grouped cathode assemblies.

Switch 182 reverses the connections to hoist cylinder assembly 117, causing the movable track section 110 to be moved upwardly. Upward movement continues until actuation of switch 185 (FIG. 25), which reverses the connection to the horizontal cylinder assembly 113 and returns the track section 110 to its original position in alignment with the channel rail 64. Switch 185 (FIG. 23), when actuated, indicates return of the transfer unit 107 to its initial position and serves to release the accumulators 86 as previously described with respect to the first 55 transfer unit 107.

An additional safety mechanism is provided by the striker plate 174 described together with the cathode unloader 150 above. The operation of this plate has been previously set out in detail.

It is obvious that modifications can be made in the physical arrangement of the various elements involved in this combination, as well as in the operational features, such as the amount of movement imparted by the various elements to the cathode assemblies during the various operations. In addition, the relative positions of the various elements can be obviously changed to meet particular requirements of an installation. The cathode conveyor might be extended so that the loading and unloading functions were accomplished at quite separate locations. 70 The present apparatus provides a rather compact collection of the various elements so that they can be readily observed by a minimum of manual effort and malfunctions in any element can be readily identified. However, the basic concepts of this disclosure are not to be lim- 75

ited by the specific features illustrated, except as set out in the following claims.

Having thus described by invention, I claim:

1. In an apparatus for mechanized stripping of electrolytically deposited metal in a metals recovery operation wherein the metal is deposited on the side faces of individual cathode assemblies, each cathode assembly comprising a flat plate suspended from an integral header bar projecting beyond both side edges thereof:

a rigid supporting framework;

cathode conveyor means on said framework for supporting and moving individual cathode assemblies along a longitudinal path relative to said framework between successive stations located thereon, the cathode assemblies being positioned on said cathode conveyor means with the side faces thereof parallel to their direction of movement;

and hydraulic stripping means on said framework at a first of said stations for removing electrolytically deposited metal from the cathode assemblies positioned along said cathode conveyor means at said first station.

2. An apparatus as set out in claim 1 wherein said cathode conveyor means comprises:

a longitudinal track and movable conveyor chain carried thereby oriented in a horizontal path including a section extending outward to each side of said first station;

a pair of longitudinally spaced hangers depending from the chain having upwardly facing ledges on which a cathode assembly header bar can rest; and stationary longitudinal rails fixed to said framework and to said track juxtaposed to said hanger along said section of track and chain to prevent the header bar of a cathode assembly supported by said hangers from being disengaged from said hangers.

3. An apparatus as set out in claim 1 wherein said cathode conveyor comprises:

a longitudinal track and movable conveyor chain carried thereby oriented in a horizontal path including a section extending outward to each side of said first station;

a plurality of paired hangers spaced along the conveyor chain having upwardly facing ledges formed to support opposite ends of cathode header bars between each pair of hangers;

and fixed guide rails on said framework extending along said section of track and chain in juxtaposition with said hangers to prevent dislodgement of a cathode header bar from said hangers to maintain the cathode plates in a vertical position during travel along said section of track;

said hydraulic stripping means comprising:

a pair of hydraulic manifolds mounted on said framework located at said first station at opposite sides of said track;

and hydraulic nozzles in communication with said manifolds having converging outlets directed toward cathode plates located on said conveyor means at said first station.

4. An apparatus as set out in claim 3 further comprising pneumatic nozzles mounted on said framework at said first station at opposite sides of said track, having outlets directed parallel to the outlets of the hydraulic nozzles at the respective sides of each cathode plate.

5. An apparatus as set out in claim 3 wherein a pneumatic nozzle is interspersed between two hydraulic nozzles at the respective sides of the track.

6. An apparatus as set out in claim 3 wherein said manifolds are mounted on said framework for vertical, transverse and angular motion relative to said framework.

7. An apparatus as set out in claim 3 wherein said manifolds are mounted on said framework for vertical adjustment relative to said framework;

and vertical positioning means operatively connected

- to said framework and manifolds to effect vertical placement of said manifolds relative to said framework.
8. An apparatus as set out in claim 3 further comprising:
5 an enclosure about that portion of the cathode conveyor adjacent the first station thereof, the manifolds and cathode assemblies located thereat to prevent spray from escaping during stripping of metal.
9. An apparatus as set out in claim 3 further comprising:
10 metal receiving and delivery means on said framework below said cathode conveyor means to collect metal stripped from cathode assemblies.
10. In an apparatus for stripping electrolytically deposited metal from cathode assemblies wherein each cathode assembly comprises a rectangular flat plate having opposite side faces on which metal is deposited and an upper header bar protruding at opposite ends beyond the respective side edges of the plate;
15 cathode conveyor means for supporting and moving individual cathode assemblies in a direction of movement parallel to the side faces thereof between a loading station, an intermediate stripping station and a final unloading station;
20 hydraulic stripping means adjacent said cathode conveyor means at said stripping station for removing deposited metal from individual cathode assemblies; supply conveyor means for carrying cathode assemblies to and from a cell room at which the metal is electrolytically deposited;
25 first means operatively connected to said cathode conveyor means and to said supply conveyor means for transferring individual cathode assemblies from said supply conveyor means to said cathode conveyor means at the loading station thereof;
30 and second means operatively connected to said cathode conveyor means and to said supply conveyor means for transferring individual cathode assemblies from said cathode conveyor means at the unloading station thereof to said supply conveyor means.
11. The apparatus as set out in claim 10 wherein the supply conveyor means includes:
35 individual carriers for carrying cathode assemblies in multiple groups;
40 and transfer means intermediate said supply conveyor means and said first means for shifting a carrier to thereby deliver a group of cathode assemblies from said supply conveyor means to said first means.
12. The apparatus as set out in claim 11 wherein said supply conveyor means comprises:
45 a track;
50 a plurality of longitudinally movable overhead trolleys suspended from said track, each having individual carriers suspended therefrom, each adapted to carry a plurality of cathode assemblies in transversely spaced parallel positions;
55 said first means comprising:
60 delivery means including stationary supports for reception of a group of cathode assemblies as carried on a single carrier;
65 and movable means on said delivery means to advance the cathode assemblies individually for loading onto said cathode conveyor;
70 said transfer means including a portion of movable track in the path of the trolleys on said supply conveyor means for shifting the position of an individual carrier supported thereby so as to cause the cathodes on the carrier to be placed on the stationary supports of said delivery means.
13. The apparatus as set out in claim 10 wherein the supply conveyor means includes:
75 individual carriers for carrying cathode assemblies in multiple groups;
and transfer means intermediate said supply conveyor

- means and said second means for receiving a group of cathode assemblies from said second means on a carrier and delivering the cathode assemblies and carrier to said supply conveyor means.
14. The apparatus as set out in claim 13 wherein said supply conveyor means comprises:
a track;
a plurality of longitudinally movable overhead trolleys suspended from the track each having individual carriers suspended therefrom, each adapted to carry a plurality of cathode assemblies, in transversely spaced parallel position;
said second means comprising:
receiving means including stationary supports for receiving a group of cathode assemblies as carried on a single carrier;
and movable means on said receiving means to advance the cathode assemblies as each is transferred from said cathode conveyor means to group the cathode assemblies;
said transfer means including a portion of movable track in the path of the trolleys on said supply conveyor means for shifting the position of an individual carrier supported thereby so as to engage and support a group of cathode assemblies from said stationary supports and to return the carrier to the track.
15. In an apparatus for mechanized stripping of electrolytically deposited metal from the side faces of cathode assemblies each comprising a flat plate suspended from an integral header bar;
a rigid supporting framework;
longitudinal cathode conveyor means for carrying individual cathode assemblies in a single line, the cathode side faces being parallel to the movement imparted to the cathode assemblies by the cathode conveyor means;
hydraulic stripping means adjacent a first station along said cathode conveyor means for removing electrolytically deposited metal from the cathodes carried thereby;
and loading means on said framework adjacent said cathode conveyor means at a second station located upstream of said stripping means for placing cathode assemblies individually on said cathode conveyor means.
16. The apparatus as set out in claim 15 further comprising:
cathode delivery means on said framework for locating individual cathode assemblies at said second station, each cathode assembly so located being in juxtaposition to said cathode conveyor means and being positioned with the side faces thereof parallel to said cathode conveyor means;
said loading means comprising:
transverse load dogs on said framework movably mounted for both transverse and longitudinal motion relative to said cathode conveyor means for engaging and supporting the header bar of a cathode assembly located by said cathode delivery means at said second station;
first driving means operatively connected to said load dogs for shifting said load dogs transversely to intersect the cathode conveyor means;
and second driving means operatively connected to said support arms operatively engageable with said cathode conveyor means for causing said load dogs to move longitudinally with the cathode conveyor means.
17. The apparatus as set out in claim 16 further comprising:
supply conveyor means on said framework to intermittently supply groups of cathode assemblies to said cathode delivery means.
18. The apparatus as set out in claim 17 wherein said cathode delivery means comprises:

21

stationary means on said framework for collecting a group of cathode assemblies from said supply conveyor means; and movable support means engageable with the group of cathode assemblies on said stationary means to advance the cathode assemblies of such group to thereby successively locate the individual cathode assemblies at said second station. 5

19. The apparatus as set out in claim 15 further comprising:

unloading means on said framework adjacent said cathode conveyor means at a third station located downstream of said stripping means for removing cathode assemblies individually from said cathode conveyor means. 10

20. The apparatus as set out in claim 19 further comprising:

cathode receiving means on said framework for supporting individual cathode assemblies at said third station, each cathode assembly so supported being in juxtaposition to said cathode conveyor means and being positioned with the side faces thereof parallel to said cathode conveyor means; said unloading means comprising: 15

cathode assembly grasping means on said framework movably mounted for both transverse and longitudinal motion relative to said cathode conveyor means for engaging and supporting a cathode assembly carried by said cathode conveyor means to said third station; 20

first driving means operatively connected to said cathode grasping means for shifting said cathode grasping means transversely to intersect the cathode conveyor means; 25

and second driving means operatively connected to said cathode grasping means for causing said cathode grasping means to move longitudinally parallel to the cathode conveyor means in the direction of movement thereof. 30

21. The apparatus as set out in claim 20 further comprising : 35

22

supply conveyor means on said framework to intermittently receive groups of cathode assemblies from said cathode receiving means.

22. The apparatus as set out in claim 21 wherein the cathode receiving means comprises:

stationary means on said framework for receiving and supporting a group of cathode assemblies from said loading means; and movable support means engageable with the group of cathode assemblies on said stationary means to advance the cathode assemblies of such group across said stationary means to thereby successively receive individual cathode assemblies at said third station. 5

23. The apparatus as set out in claim 19 further comprising:

a plate on said framework downstream of said third station intersecting the path of movement of the cathode assemblies on said cathode conveyor means for detecting the presence of cathode assemblies beyond said third station, said plate being operatively connected to said unloading means and to said stripping means to render said unloading means and said stripping means inoperative when contacted by a cathode assembly. 10
